UNITED STATES PATENT OFFICE.

JAMES WILLIAM BUNT, OF DENVER, COLORADO.

ROCKER-SWING.

1,369,616.

Specification of Letters Patent. Patented Feb. 22, 1921.

Application filed May 20, 1920. Serial No. 382,956.

To all whom it may concern:

Be it known that I, JAMES WILLIAM BUNT, a citizen of the United States, and a resident of Denver, in the county of Denver and State of Colorado, have invented a new and Improved Rocker-Swing, of which the following is a full, clear, and exact description.

This invention relates to improvements in rocker swings, an object of the invention being to provide a swing which will maintain a pendulum-like momentum for a relatively long period when said movement is initiated and require but slight exertion to operate the swing.

A further object is to provide an improved construction of swing of the lawn type which is strong and durable in use, which is relatively light in weight, and neat and attractive in appearance.

With these and other objects in view the invention consists in certain novel features of construction, and combinations and arrangements of parts as will be more fully hereinafter described and pointed out in the claims.

In the accompanying drawings—

Figure 1 is a view in front elevation illustrating my invention.

Fig. 2 is a view in section on the line 2—2 of Fig. 1.

Fig. 3 is an enlarged fragmentary view in vertical section illustrating by full lines and dotted lines the movement of one of the rockers.

A represents a supporting frame composed of four uprights 1 preferably of angle iron connected at their lower ends by base bars 2 extending both longitudinally and transversely of the frame and angle plates 3 are securely riveted in the corners of the frame providing a strong and rigid structure. Diagonal braces 4 are also provided which are crossed and connect the uprights 1 at the sides of the frame.

Angle bars 5 are secured to the upper ends of and form portions of the frame and these angle bars 5 constitute rails on which my improved rockers 6 are mounted. The rockers 6 have curved lower edges 7 which are supported on the horizontal base flanges of the rails 5 and the vertical flanges 8 of said rails prevent lateral movement of the rockers as will more fully hereinafter appear.

Four vertical hangers 9 are supported by

the rockers 6 and at their lower ends support a suitable seat 10. Rods 11 extend through the upper ends of the hangers 9 and through the rockers 6 and are secured in place by means of nuts 12 screwed onto the threaded ends of the rods.

Spacing sleeves 13 are positioned on the rods 11 and interposed between the hangers 9 and the rockers 6, and nuts 14 are screwed onto the rods against the inner faces of the hangers to effectually clamp the parts in proper relative position. Below the rods 11 the hangers and rockers are connected by shorter bolts 15 extending through the rockers and the hangers and secured by nuts 16, and spacing sleeves 17 are provided on these bolts 15 to hold the hangers and rockers in proper relative positions.

The upper end of the frame A is strengthened by transversely positioned rods 18 extending through the angle plates 3 at the upper ends of the frame. These rods 18 are positioned parallel to each other and provided with spacing sleeves 19.

It will be noted particularly by reference to Figs. 2 and 3, that the rods 18 with their spacing sleeves 19 are located inside or within the pair of hangers 9, but spaced from the hangers to allow the necessary rocking movement of the swing, but limit such movement and prevent possibility of the longitudinal displacement of the rockers relative to their rails 5.

It will be noted, particularly by reference to Fig. 1, that while I provide four vertical hangers 9, these hangers may be formed by a pair of U-shaped members with the lower or intermediate portions 20 extending under the seat 10 and supporting the same, thus reducing the number of parts and giving added strength to the swing.

By reason of the construction above described, momentum imparted to the swing will cause the rockers to rock back and forth on the rails 5 and thus maintain the pendulum-like momentum for an indefinite period and by reason of this construction the action of the swing requires but slight manual labor and a smooth rocking action is had as friction is reduced to a minimum.

Various slight changes might be made in the general form and arrangement of parts described without departing from the invention, and hence I do not limit myself to the precise details set forth, but consider my

self at liberty to make such changes and alterations as fairly fall within the spirit and scope of the appended claims.

I claim:

- 5 1. The combination with a supporting frame, a pair of rails at the top of the frame, rockers mounted on the rails, hangers suspended from the rockers, a seat secured to the hangers, a pair of rods located in the
- 10 frame and positioned between the hangers limiting the longitudinal movement of the rockers, and bracing the frame.
- 15 2. The combination with a supporting frame, a pair of rails at the top of the frame, rockers mounted on the rails, hangers suspended from the rockers, a seat secured to

the hangers, said rails composed of angle irons, and rods connecting the rockers above the angle irons and compelling them to rock in unison.

- 20 3. In a swing, a frame composed of angle iron bars, strengthening plates at the angles of the bars, crossed braces connecting the vertical bars of the frame, the upper angle bars of the frame constituting rails, rockers mounted on the rails, hangers secured to and spaced from the rockers, a seat supported by the hangers, rods extending through the upper angle plates, and spacing sleeves on the rods limiting the longitudinal movement 25 of the rockers.

JAMES WILLIAM BUNT.
